UNITED STATES PATENT OFFICE.

REINHARD SCHNEIDER, OF ALLEGHENY, PENNSYLVANIA.

COMBINED BILLIARD AND POOL TABLE.

No. 895,110.

Specification of Letters Patent.

Patented Aug. 4, 1908.

Application filed April 12, 1906. Serial No. 311,248.

To all whom it may concern:

Be it known that I, REINHARD SCHNEIDER, a resident of Allegheny, in the county of Allegheny and State of Pennsylvania, have invented a new and useful Improvement in a Combined Billiard and Pool Table; and I do hereby declare the following to be a full, clear, and exact description thereof.

My invention relates to combined billiard and pool tables and has for its object to provide a cheap and simple form of such table whereby it can be readily, conveniently and quickly transformed into a billiard or pool table, and without the employment of special devices or complicated mechanisms or parts.

My invention consists, generally stated, in the novel arrangement, construction and combination of parts, as hereinafter more specifically set forth and described and particularly pointed out in the claims.

To enable others skilled in the art to which my invention appertains to construct and use my improved table, I will describe the same more fully, referring to the accompanying drawing, in which—

Figure 1 is a plan view of a table showing my invention applied thereto. Fig. 2 is an enlarged cross-section through the rail and cushion showing the manner of holding said cushion in position. Fig. 3 is a side-elevation of the connecting bolt and its connections for holding said cushion. Fig. 4 is another like view of the same showing it in another position. Figs. 5 and 6 are views of the slotted plate employed with the cushion for the connecting bolt.

Like symbols of reference herein indicate like parts in each of the figures of the drawing.

As illustrated in said drawing A represents my improved table which is provided with the usual rail 1 extending above and around the usual slate bed 2 resting upon the frame 3 which rail is provided with the usual cloth cover 2' over the same and secured to said frame 3. The table A is provided with the usual pockets 4 therein and leading to said pockets are the openings 5 which are formed in the rail 1 and bed 2.

Resting upon the bed 2 and extending around and within the table A are the cushions 6, which are composed of the usual blocks 7 on which are carried and secured in the ordinary manner the strips of rubber 8, while extending over and around said rubber strips and attached to said blocks is the usual cloth cover 9. These cushions 6 are of

different lengths for the sides and ends of the table A, the longer ones being adapted for use on the table when used for billiard playing and having their ends cut at an angle, as at 10, for meeting with each other and closing the entrance to the pockets 4. The other or shorter cushions 6 are adapted for use in pool playing and such angular cut ends 10 are adapted to then be in line with the angular cut ends 10' formed on the rails 1 in order to enable the balls to be run into said pockets 4.

The cushions 6 are adapted to be removable from the rail 1 and are attached and detached from upwardly extending sides of said rail through the medium of a series of locking means or devices 11 extending around the table A and one of which is shown in Fig. 3. These devices 11 are composed of a bolt 12 which extends through an opening 12' formed in the rail 1 and under the projecting flange 1' formed on the outer face of said rail and is provided with a head 13 at its inner end which is adapted to be passed through a slotted opening 14 formed in a plate 15 and 80 is seated in a recess 16 in the rear of said plate and formed in the block 7 of the cushion 6. The plate 15 is preferably of circular form and is secured in a seat 15' formed in the face of the block 7 by screws 15" passing through said plate and taking into said block. The outer end of the bolt 12 extends beyond the outer face of the rail 1 and through a washer or plate 17, extending around said bolt and such end has a pivot pin 18 passing through the same on which is mounted eccentrically the locking lever 19. This lever 19 is preferably bifurcated or forked, as at 19', in order to permit the pin 18 to extend through both sides of the same, and such forked portions are provided with the cam faces 20 thereon for engaging with the plate 17 when such lever is in its locked position.

The manner of assembling the parts and using my improved combined billiard and pool table is as follows:—In case it is desired to use the table A for billiard playing the longer cushions 6 are placed in position within the table and directly against the sides of the rail 1 so that their angular ends 10 will 105 come against each other and sit over the pockets 4 in said table to close access of the playing balls to the same. After the cushions 6 are thus in position and in order to hold the same securely in place each of the 110 bolts 12 is pushed inwardly through its opening 12' so that its head 13 passes through the

slotted opening 14 in the plate 15 on said cushions and enters the recess 16 in the rear of said plate as shown in Figs. 2 and 4. The bolts 12 can then be turned by their levers 19 5 within their openings 12' so that the heads 13 thereon will be placed at right angles to the slotted opening 14 in the plates 15 and within the recesses 16, after which each of said levers can be pushed back to the position shown by dotted lines in Fig. 3. This 10 will permit the cam faces 20 on the levers 19 to engage with the plates 17 on the bolts 12 and will force said plates against the face of the rail 1 while the heads 13 on said bolts within 15 the recesses 16 will thereby be brought against the body of the plates 15 and thereby lock and securely hold the cushions 6 directly against said rail.

When it is desired to detach and remove 20 the cushions 6 from the rail 1 for converting the table A into a pool table or for any other purpose, all that is required is to pull out the levers 19 to the position shown in Fig. 2 and turn the bolts 12 so that the heads 13 thereon 25 will come opposite the opening 14 in the plates 15. After this is done the cushions 6 can be removed from the rail 1 and table, and the cushions for pool playing placed on the table and against the sides of said rail, so 30 that when in position such cushions will have their angular ends 10 come in line with the angular ends 10' on the rails 1' to permit access of the playing balls to the pockets 4, and then said cushions can be secured and 35 locked in place on said rail in the manner herein before described.

It will be obvious that in case it is desired 40 to remove any one or all of the bolts 12 from the rail 1 for the purpose of repairing or replacing the same it can be accomplished 45 by simply forcing out the pivot pins 18 through the levers 19 and ends of said bolts, when said bolts can be forced inward through their openings 12' in the rail and be removed 50 from therefrom.

It will thus be seen that my improved 55 combined billiard and pool table can be converted into one or the other form easily and rapidly and by any unskilled person, as practical experience has proven, and it does not require any special design of table or cushion as in ordinary cases, or the employment of separate blocks or parts of cushions for fitting between the cushions proper and over the pockets.

The parts are simple and easy to handle and operate and will not be liable to come

in contact with the person or wearing apparel of the parties using the same. The parts are also strong and durable and will 60 not get out of order, while at the same time the cushions are held securely locked in place and will be as firm for playing upon as if permanently attached to the table.

Various modifications and changes in the construction and design of my combined billiard and pool table may be resorted to without departing from the spirit of the invention or sacrificing any of its advantages.

What I claim as my invention and desire 70 to secure by Letters Patent is:—

1. In a combined billiard and pool table, the combination of the rail, cushions fitting directly against said rail, bolts on said rail and connected to said cushions, and cam 75 devices on said bolts for holding said cushions against said rail and for permitting the same to be detached therefrom.

2. In a combined billiard and pool table, the combination of the rail, cushions fitting 80 directly against said rail, plates on said cushions, bolts on said rails having heads thereon for engaging with said plates, and cam-devices on said bolts for holding said cushions against said rail and for permitting 85 the same to be detached therefrom.

3. In a combined billiard and pool table, the combination of the rail, cushions fitting 90 directly against said rail, plates on said cushions having slotted openings therein, 95 bolts on said rail having heads thereon for passing through said openings and into said cushions, and cam-levers on said bolts for locking the cushions in position against said rail and for permitting the same to be detached therefrom.

4. In a combined billiard and pool table, the combination of the rail, cushions fitting directly against said rail, plates on said 100 cushions having slotted openings therein, bolts on said rail having heads thereon for passing through said openings and into said cushions, washers or plates on said bolts and adapted to engage with said rail, and cam-levers on said bolts for engaging with 105 said washers to lock said cushions in position against the rail and for permitting the same to be detached therefrom.

In testimony whereof, I the said REINHARD SCHNEIDER have hereunto set my hand.

REINHARD SCHNEIDER.
